UNITED STATES PATENT OFFICE.

ARTHUR C. DENNIS, OF SAN FRANCISCO, CALIFORNIA.

LOADING AND DISCHARGING APPARATUS.

Application filed November 5, 1923. Serial No. 672,898.

To all whom it may concern:

Be it known that I, ARTHUR C. DENNIS, a citizen of the United States, residing at San Francisco, in the county of San Francisco and State of California, have invented new and useful Improvements in Loading and Discharging Apparatus, of which the following is a specification.

This invention relates to improvements in loading machines or apparatus and has to do more particularly with an improved car loader.

The device of my invention includes, in its practical form, an excavator or scraper means acting in concert with an improved conveyor structure for conveying and depositing the material to the desired point of deposition.

The device of my invention is especially designed for tunnel or other underground work in which cars are employed to receive the material from the conveyor. In this character of work it is frequently necessary to wait for empty cars and this delays the operation of excavation until a car arrives. Further, when cars arrive slowly so that continuous operation of the apparatus cannot be carried on, the delay or slowing up increases the cost of the work to the contractor.

Therefore, it is a special feature of my invention to provide a conveyor which can be operated substantially continuously, thereby permitting substantially continuous scraping, and yet which can be speeded in accordance with the number and capacity of cars available. Thus, when cars arrive slowly, my improved conveyor will be advanced step by step while being loaded, so that the material loaded thereon will be held in storage and will form a substantially continuous and uninterrupted strip of material. When a car arrives, the conveyor will be quickly and continuously advanced sufficiently to dump a car full, and then the conveyor will be retracted back to the loading point, or sufficiently toward such point so that the excess material on the conveyor, that could not be accommodated by the car, will be in a position to form a continuation with new material about to be loaded onto the conveyor. Thus it will be seen that my improved conveyor may be termed a storage conveyor in that it serves in a storage capacity for material until the latter accumulates sufficiently to fill or more than fill a

car, and also for excess material which the car cannot hold.

My invention has many other features of novelty which will be more fully described in connection with the accompanying drawings and which will be more particularly pointed out in and by the appended claims.

In the drawings:

Fig. 1, is a view in elevation of the preferred form of my invention showing the loaded scraper just approaching the skid or guide.

Fig. 2, is a view in elevation showing the loaded scraper advanced along the skid to a dumping position.

Fig. 3, is a plan view of that portion of the apparatus shown in Figure 1.

Fig. 4, is a sectional view on line 4—4 of Fig. 1.

Fig. 5, is a sectional view on line 5—5 of Fig. 1.

Fig. 6, is a sectional view on line 6—6 of Fig. 1.

Fig. 7, is a view partly in section on line 7—7 of Fig. 1.

Fig. 8, is a front face view of the scraper.

Fig. 9, is a view in side elevation thereof.

Like characters of reference designate similar parts throughout the different figures of the drawings.

As shown, my improved apparatus includes a main wheeled frame generally designated at 1, and adapted to be advanced toward a dump or muck pile 2, on rails 3, said main frame 1, may comprise a horizontal portion 4, suitably mounted on wheels 5, and likewise suitably laterally braced. Said frame may include uprights 6 connected by a transverse member 7, on which is supported a suitable power scraper cable winch mechanism, generally designated at 8, and which will be later referred to. An operator's platform 9, is mounted in accessible proximity to said mechanism, as clearly shown, and the apparatus is designed so that the operator can control the entire mechanism while standing on this platform. Uprights 10, on that end remote from uprights 6, are suitably connected at 11, and form a boom support to which a boom 12, is pivotally connected.

A skid or guide way for the scraper is mounted on said frame 1, and may include angle irons 14, secured to uprights 6 and 10 and to intermediate members 15. Suitable braces 16, may be employed to brace the

boom supports 10, said members being connected with said uprights 10 and with the skid irons 14. The skid irons 14 are floored, as indicated at 17, from points 18 to 19. 5 The horizontal portions 20, of the irons 14, form the guides proper. To the left of end 19, of the floor, there is an open space between the irons 14 through which the contents of the scraper can dump or descend 10 onto the receiving end of the conveyor, as will be later described. I provide an apron or shoe 22, at the entrance of the skid onto which the scraper can be advanced to the skid. The forward edge of this apron may 15 ride on the rails 3, and said apron may be mounted on bars 23, hinged at 24, to the skid, and having a cross stop bar 25, extending under the skid to prevent a too great descent of the front end of the apron. 20 A boom supporting yoke is pivoted at 24, and may comprise uprights 26, and a cross member 27, extending beneath boom 12, and connected therewith by a U-bolt 28, which need not be described in detail as the same 25 is not herein claimed. Guide bars 29, mounted on uprights 26, serve to guide the scraper onto the apron and into a position of registry with irons 14.

I have indicated a scraper at 30, which 30 is one of the reversible types known as the Sullivan, and which need not be described in detail. The forward portion of the scraper is connected with a cable 31, trained about sheave 32, of the power winch 8, 35 A cable 33, is connected with the rear end of the scraper and is trained about a sheave 34, on boom 12, and supported on idle rollers 35 and 36, mounted on boom 12. This cable extends to and is trained about sheave 37, 40 of winch 8. This winch may be electrically, air or otherwise driven mechanism, not material to this case, and will have operating levers or switches whereby it may be controlled by the operator on platform 9, to 45 cause the scraper 30 to be advanced along the skid into a dumping position and back along the skid to the muck dump. It will be clear that the foregoing scraper mechanism constitutes means controllable at the 50 will of the operator for intermittently loading the conveyor, which I will presently describe.

My improved conveyor includes a conveyor frame 38, having a loading or intake portion 39, connected with the main frame 1, in subjacent relation to the discharge space at the left of the floor 19, of the scraper guide-way 14. The conveyor frame 38 is inclined upwardly and rearwardly 55 from the main frame, as clearly shown in Fig. 1, the elevation of the rear or delivery end 40, of the conveyor frame, is sufficient 60 to overhang a car indicated at 41. I provide means which may take the form of a 65 wheeled supporting truck 42, for support-

ing the overhanging portion of the conveyor frame and I preferably couple said truck 42, with the main frame truck 1, as indicated at 43, whereby the supporting truck will at all times be in predetermined relation with the main frame truck 1. In order to relieve the apparatus from strain, which would result from hastily laid rails 3, I preferably pivotally connect truck 42, with the conveyor frame. To this end, the frame 38, is provided with pendent bearings 44, and the truck 42, is provided with bearings 45, through which bearings a pivot shaft 46 extends and is journalled. An endless conveyor apron 47, of any suitable type, has its receiving bight 48, trained about a suitable wheel structure 49, journalled in the conveyor frame 38. The remaining bight 50, is trained about a wheel structure 51, mounted on shaft 52, which is journalled at 53. Frame 38, is provided with guards in the form of angle irons 54, which overhang the edges of the conveyor apron 47, as will be clearly seen by reference to Fig. 6. The frame 38, also has side extensions 55, which may be in the form of angle irons, for the purpose of enabling the structure to "take" a greater depth of material. An idler supporting roller 56, is provided to engage and support the lower lap of apron 47, so that it will clear the top of truck 42. This roller may be supported by brackets 57.

On one side of the rear end of frame 38, is a motor 58, which for the purpose of this invention may be any type capable of imparting a continuously slow or step by step motion to the apron 47. This motor is directly connected with shaft 52 to drive the latter in one direction of revolution. If it be an air motor, a controlling pipe 59, may extend to platform 9, and terminate in a controlling valve 60. A similar motor 61, on the opposite side, is directly connected with the remaining end of shaft 52, and has a controlling pipe 62, extending forwardly to platform 8, and terminating in a controlling valve 63. It will be understood that wheels 51, will have teeth so that rollers 64, on apron 47, will engage said teeth and thereby constitute a positive drive.

It will thus be seen that I have provided, broadly speaking, driving mechanism, preferably at the delivery end of the conveyor, for operating the conveyor apron in either of two directions, which is a claimed feature of novelty. This drive is of such a character that the apron 47 can be intermittently advanced toward a dumping position, or continuously so advanced. By locating the motors on the delivery end of the conveyor, I am able to exert a pull through the shortest length of apron as between the bight thereof and the load thereon, which is a great advantage in that much friction is avoided

as compared to the same construction with the motors on the intake end of the conveyor.

Explaining the operation in connection with the apparatus as shown, with a scraper loader, it will be seen that as each scraper full is dumped onto the receiving portion of the apron 47, the motor 58, will be energized to advance the apron a short step or distance toward the delivery end in order to present a vacant apron space to the next scraper load, thereby making the strip of material X, continuous. Hence, the conveyor apron 47, functions as a storage device for holding the material loaded, after and also during the time of dumping the new material. The conveyor apron might, in some instances, be loaded to an extent beyond that indicated in Fig. 1. This is a novel feature over all other conveyors, of this general type, known to me, as in all prior types, the conveyor is continuously operating and cannot be operated sufficiently slowly, or step by step, in order to perform the functions set forth.

Suppose a car had been located as shown at 41, in receiving relation with the delivery end of the conveyor, then the operator would energize motor 58, to continuously and quickly advance apron 47 until enough of the material X had been discharged into car 41, to completely fill the same. Suppose there was more than enough material on the apron to fill car 41, then, and in that event, the operator would not stop and wait for the next car, but he would energize motor 61, and return apron 47, with its excess material back to the position shown in Fig. 1, or into such position that the right hand end of the excess material would be in a position to form a continuation with the next scraper full dumped onto the conveyor apron. Thus, it will be seen that in deference to the best economy and to obtain the greatest efficiency, the material will preferably always be in the form of a continuous strip. It will be understood that during the short period of filling the car 41, the scraper 30, will be idle, or may be slowly approaching a dumping position.

It will now be clear that with a large capacity machine, a car need not be delayed to be filled, and that by reason of the storage feature, the operation of scraping the muck from pile 2, may be carried on practically continuously. This is especially valuable when for some reason the cars are delayed, aside from the equally important and obviously great advantage of maintaining this costly apparatus in practically constant operation.

It is believed that my invention will be fully understood from the foregoing description, and while I have herein shown and described one specific embodiment of

my invention, I do not wish to be limited thereto except for such limitations as the claims may import.

I claim:

1. In a car loading machine, a conveyor having a discharge end for delivery of material into a car, means for loading material onto said conveyor at a point remote from the discharge end thereof, means for advancing the conveyor toward the discharge end to dump sufficient material to fill a car, and means for retracting the conveyor with the remainder of the material thereon back to the loading point to store the excess material adjacent to the point where new material is loaded onto said conveyor.

2. A car loading machine having means for loading material, a conveyor for receiving the material from said means and conveying it to a car, and mechanism for actuating said conveyor in either of two directions to fill the car and return the excess material back into proximity to the new material being loaded onto said conveyor by said means.

3. A car loading apparatus comprising in combination, a wheeled frame adapted to be advanced toward the dump, a conveyor on said frame having a receiving and a delivery end, means for loading material onto the receiving end of said conveyor, means at the delivery end of said conveyor for advancing the latter sufficiently to dump a car full of material, and means on the delivery end of said conveyor for retracting the latter with the excess material thereon back to near the proximity of the newly loaded material.

4. In a car loading apparatus, a storage conveyor having a discharge end for delivery into a car and also having a receiving end, means for intermittently loading material onto the receiving end of said conveyor at the will of the operator, means at the will of the operator for successively advancing said conveyor step by step toward its discharge end in accordance with the amount of material loaded onto said receiving end and in a manner to form a continuous strip of material to be held in storage until a car arrives, said means being adapted to quickly advance the conveyor after a car arrives to discharge enough of the stored material to fill the car and retain the excess on said conveyor, and means for retracting said conveyor back toward the loading point sufficiently so that the newly loaded material will again form a continuation with the excess material carried back on said conveyor.

5. In a loading apparatus, a wheeled main frame, a conveyor frame mounted on said main frame and having a discharge end, an endless conveyor on said conveyor frame, a shaft structure at the discharge end of said

conveyor frame about which the discharge end of said endless conveyor is trained; a motor on one side of said conveyor frame and connected with one end of said shaft 5 structure for driving the latter in one direction of revolution, and a motor on the other side of said conveyor frame and connected

with the remaining end of said shaft structure for driving the latter in a direction of revolution opposite to the first named direction of revolution. 10

In testimony that I claim the foregoing as my own, I hereby affix my signature.

ARTHUR C. DENNIS.
